RAINPROOF CAP AND KNOCKOFF FOR
PITMEN OR SUPPORTSBert G. Goble, Tulsa, Okla., assignor to
W. A. Quigley

Application July 5, 1929. Serial No. 376,096

2 Claims. (Cl. 308—21)

My invention relates to the art of applying a bath of oil to the top and bottom bearings of a pitman support or arm which slightly shifts its vertical position.

Moreover, I provide a rainproof roof over these bearings so that when it rains the water will not wash the oil out of its receptacle and cause the bearing to run in a bath of water.

The usual support for a rod line or a pitman as used with the ordinary pumping jack consists of an upright pivoted at its lower end in an open bearing and having clamping means pivoted at its upper end. The reciprocating rod line is tightly clamped in the clamping means and as the rod line moves to and fro it causes the support to oscillate about the open bearing at its lower end.

One objection to the structure just set forth is that the bearings are exposed to the weather and the water washes the oil out of the bearings. In the ordinary type of bearings which run in a bath of oil, any rain which may collect in the oil reservoir will force the oil out. In the more widely used type of bearings no oil bath at all is used and obviously these are very inefficient even if oiled frequently as they have no means to retain the oil.

Another objection to the present day supports or uprights is that they are pivoted to their foundations and to the shackle lines so that they will not come apart even when the shackle lines break and this usually breaks up some of the castings and tears up things in general as many of these rod lines have a 10,000 to 20,000 pound strain on them and even if allowed to move only a few feet when they break the sudden stop snaps some of the equipment in two.

Another objection to the supports now in use is that there is no easy way to clamp them to the shackle rod lines and it is often necessary to shift the top of the support along the shackle line.

My type of clamp has been previously set forth in my application filed August 31, 1928, entitled Shackle line equalizer, Serial No. 303,307.

My aim is to provide a support which will eliminate the above recited difficulties and which will be easily and cheaply constructed.

My invention consists of an open bottom bearing, a top journal with an integral roof and clamping means and a middle angle portion. This angle portion has an open bearing at its top which is complementary to the top journal, and a top journal with an integral roof, which is complementary to the bottom bearing.

Another advantage of my device resides in the integral roofs or webs which are provided to shield the bearings from rain and the like.

Another feature of my invention is my novel means whereby the lower journal will be lifted from its seat when excessive oscillation of the upright occurs. This means consists of a semi-circular web which not only serves as a roof, but also abuts against the bottom bearing and consequently lifts the lower journal from its seat. It will be noted that the lower journal is undercut in order to take care of any sidewise movement which may occur when these two parts separate. Also, I provide ribs underneath the roof which also aid in separating the two parts when breakage occurs. By this latter method more oscillation movement may be obtained and hence a deeper vat of oil for the journal to submerge in may be obtained.

Still further objects or advantages subsidiary or incidental to the aforesaid objects, or resulting from the construction or operation of the invention as it may be carried into effect, will become apparent as the said invention is hereinafter further disclosed.

I attain these objects by the mechanism illustrated in the accompanying drawing, in which—

Fig. 1 is a perspective view of my swinging support with the several parts in detached position.

Fig. 2 is a cross sectional view taken through the center of my support.

Fig. 3 is a view taken along the line 3—3 of Fig. 2.

Fig. 4 is a diagrammatic view of the base in its journal.

Fig. 5 is a view similar to Fig. 4 but disclosing how the web and rib cause the journal to rise out of its bearing.

Fig. 6 is a perspective view showing a modification of my invention.

Similar numerals represent similar parts throughout the several views.

An open bearing box 10, has a recess 11, and flanges 12, and 13, at opposite sides thereof. Bolts 14, and 15, pass through the flanges 12 and 13, respectively, and hold the open bearing 10, firmly to its base 16.

The recess 11, as clearly shown in Fig. 1, is filled with oil and provides a seat for the lower journal 17. This journal 17, has a hole 18, therein which provides an additional space for the lubricating oil. The upper part of the journal is undercut as indicated at 19, and has a semi-circular roof or web 21, which extends outwardly over the bearing and its journal to protect them

from rain and the like. See Figs. 2, 4, and 5. This lower journal member is designated generally by the numeral 8. It will be noted that the undercutting of the journal 17, causes all friction between the journal and its bearing to occur below the surface of the lubricant.

The roof or web 21, is further supported and connected with the journal 17, by means of braces or members 50 and 51. These braces or members serve both to strengthen the roof and also serve to 'knock-off' or lift out the journal from its seat or bearing when the rod line parts. They act in conjunction with the edge of the roof in this respect.

15. The rectangular upper portion 22, is integral with the journal 17, and the roof 21, and it has a hole 23, therethrough. A square boss 24, is symmetrically located about the hole 23, and prevents the head of the bolt 25, from rotating.

20. An angle 27, is fastened to the part 22, by means of bolts 25. This angle may be of any desired length. The top of this angle is fastened to the bearing 30, by means of bolts 28 and 29. All of these connecting bolts are considerably smaller than the holes in which they are placed as this allows the angle to be slightly adjusted relatively to the top bearing and bottom journal.

This bearing 30, has a recess 31, into which the hollow journal 32, is revolvably mounted. A neck portion 34, which is narrowed slightly as at 33, connects the journal 32, to the body portion 35. This body portion 35, has a groove 36, and a hole 37, therein. A seat 38, provides a home for the lower end of the clamping block 39, and a hole 40, in the top of this block matches the hole 37, whereby tightening means may be placed therein. The block 39, also has a groove or seat 41, which is in alignment with the groove or seat 36, and into which the rod line 42, may be clamped. A web or roof portion 45, is formed integral with the body portion 35, the neck portion 34, and the journal 32. Braces or webs 60 and 61 interconnect the roof portion 45, and the journal 32, and act or function similarly to the braces or members 50 and 51.

45. This upper journal member is designated generally by the numeral 7. Fig. 6 illustrates how my invention may be applied to a journal 70,

for a pipe, 79. This journal 70, is formed integrally with the roof, 71, and ribs 72 and 73 brace the same and also serve as means to lift the journal from its seat when excessive movement occurs.

80. A curved semi-cylindrical flange 74, extends upwardly and co-operates with the complementary casting 75, to hold the pitman or pipe 79 therebetween.

Operation

85. When it is desired to utilize my improved support its base is fixedly mounted and the upper journal member 7, is clamped to the reciprocating rod line 42. Recesses 31, and 11, are filled with lubricant. When the rod line moves to and fro, as indicated by the arrows A and B, the top journal remains in a vertical position by turning in the recess 31, the lower journal 17, also turns relative to the recess or the bearing which contains it until the web 21, comes in contact with the base 10. This occurs only when the rod line parts or breaks. When this occurs the journal 17, is lifted clear of its seat and the support may then drop to the ground and escape injury.

90. Having thus revealed this invention, I claim as new and desire to secure the following combinations and elements or equivalents thereof, by Letters Patent of the United States.

95. What I claim is:—

100. 1. In a shackle line support having a hollow base and a journal therein the combination of means attached to the journal extending out over and downwardly around the juncture between the base and the journal whereby rain 110, and the like is kept from entering the hollow base, said extending means being adapted to contact with the base when a certain position is reached thereby unseating the journal.

105. 2. A support for rod lines or the like comprising a base having an open recess therein, a journal adapted to rest in the recess, a neck on the journal, a curved roof integrally formed with said neck, and depending end portions across the curved roof whereby the said open recess is 110: shielded from rain and the like.
